CLAIM

The ornamental design for a low profile surface mount light fixture with touchless control, as shown and described.

DESCRIPTION

FIG. 1 is a perspective view of a low profile surface mount light fixture with touchless control, showing my new design;

FIG. 2 is an end elevational view of the invention;

FIG. 3 is a front view of the invention;

FIG. 4 is the top plan view of the invention;

FIG. 5 is the rear view of the invention; and,

FIG. 6 is the bottom plan view of the invention.
